CLAIM

The ornamental design for a paper product, as shown and described.

DESCRIPTION

The SOLE figure is a top plan view of a paper product showing our new ornamental design.

The broken line showings are for illustrative purposes only and form no part of the claimed design. The broken lines shown along the border of the figures depict the boundaries of one repeat unit of the claimed design and indicate that the design may continue indeterminately in one or more directions. The broken lines form no part of the claimed design.

The surfaces or portions not shown in the drawings or described in the specification form no part of the claimed design.
